HIS ATTORNEY

UNITED STATES PATENT OFFICE

151,527

DESIGN FOR A LAWN SWEeper

Edwin D. Parker, Springfield, Ohio, assignor to
The Parker Pattern and Foundry Company,
Springfield, Ohio, a corporation of Ohio

Application January 8, 1947, Serial No. 135,995

Term of patent 14 years

(Cl. D40—1)

To all whom it may concern:

Be it known that I, Edwin D. Parker, a citizen of the United States, residing at Springfield, in the county of Clark and State of Ohio, have invented a new, original, and ornamental Design for Lawn Sweeper, of which the following is a specification, reference being had to the accompanying drawing, forming part thereof.

The figure is a perspective view of the lawn sweeper, showing my new design.

I claim:

The ornamental design for a lawn sweeper, as shown.

EDWIN D. PARKER.
